CLAIM

The ornamental design for a cosmetic bottle, as shown and described.

DESCRIPTION

FIG. 1 is a top perspective view of a cosmetic bottle, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top, exploded top perspective view thereof;

FIG. 10 is an exploded bottom view thereof;

FIG. 11 is an exploded front view thereof;

FIG. 12 is an exploded rear view thereof;

FIG. 13 is an exploded left side view thereof;

FIG. 14 is an exploded right side view thereof;

FIG. 15 is an exploded top view thereof; and,

FIG. 16 is an exploded bottom view thereof.

The dot-dash broken lines immediately adjacent to the claimed areas in the views represent the boundaries of the design and form no part thereof.

None of the broken lines form any part of the claimed design.

1 Claim, 12 Drawing Sheets
